Primary Examiner — Dana K Weiland*Assistant Examiner* — Jenny lou M Binas(74) *Attorney, Agent, or Firm* — Banner & Witcoff, Ltd.(57) **CLAIM**

The ornamental design for a robotic cleaner, as shown and described.

DESCRIPTION

FIG. 1 is a perspective view of a robotic cleaner in accordance with the present invention;

FIG. 2 is a front view thereof;

FIG. 3 is a rear view thereof;

FIG. 4 is a left view thereof;

FIG. 5 is a right view thereof; and,

FIG. 6 is a top view thereof.

The features shown in broken lines are for illustrating portions of the robotic cleaner that form no part of the claimed design.

1 Claim, 6 Drawing Sheets(56)
